UNITED STATES PATENT OFFICE.

FREDERIC H. BENDER, OF CHICAGO, ILLINOIS, ASSIGNOR TO AMERICAN STEEL FOUNDRIES, OF CHICAGO, ILLINOIS, A CORPORATION OF NEW JERSEY.

BRAKE-HANGER BRACKET.

Application filed April 12, 1923. Serial No. 631,513.

To all whom it may concern:

Be it known that I, FREDERIC H. BENDER, a citizen of the United States, residing at Chicago, in the county of Cook and State 5 of Illinois, have invented certain new and useful Improvements in Brake-Hanger Brackets, of which the following is a specification.

This invention relates to brake hanger 10 brackets.

In the application of brake hangers to their supports, among other things, it is essential to consider proper clearance to accommodate movements of the brakes when 15 the brake shoe and wheels are new and when worn, and also to consider the safety with which the brake hanger is held by its support to prevent falling of the brake mechanism and possible wrecking of a train, and at 20 the same time consider the rapidity with which parts may be assembled and disassembled.

One object of the invention is to provide simple, novel and efficient means for securely supporting brake hangers to meet the requirements above mentioned.

Another object is to provide a simple brake hanger arrangement in which the parts are interlocked in a manner which insures safety 30 in addition to a rapid assembly and disassembly of the parts, and in general adapted to meet the various requirements for successful use under service conditions.

These and other objects are accomplished 35 by means of the arrangement disclosed on the accompanying sheets of drawings, in which—

Figure 1 is a transverse sectional view through a side frame showing a brake hanger bracket and means for securing the 40 brake hanger therein;

Figure 2 is a bottom plan view of the arrangement shown in Figure 1;

Figure 3 is a sectional view taken in the 45 plane of line 3—3 of Figure 1;

Figure 4 is a diagrammatic view showing the brake hanger in three different positions, which will be referred to later;

Figure 5 is a view similar to that shown 50 in Figure 1 but showing a modification of the invention;

Figure 6 is a bottom plan view of the arrangement shown in Figure 5; and

Figure 7 is a side elevation of a portion

of the side frame, the brake hanger bracket, 55 the brake hanger and its keeper.

The various novel features of the invention will be apparent from the following description and drawings and will be particularly pointed out in the appended claims. 60

Referring generally to all the figures of the drawings, it will be noted that the invention is disclosed in connection with a side frame 10 having an integrally formed brake hanger bracket 11, having upper and lower 65 jaws 12 and 13, respectively, which are spaced to provide an opening 14 which extends from one side of the bracket or support rearwardly between the jaws. A transverse groove or semi-cylindrical slot 70 15 is provided in the lower jaw 13 for the reception of the upper horizontal portion 16 of the brake hanger, which, in this instance, has two downwardly extending arms 17 which terminate in a lower horizontal 75 portion 18' for attachment to a brake head in the usual manner.

It is apparent from all the figures of the drawings that the upper horizontal portion 16 of the brake hanger is passed through 80 the open side of the support between the jaws 12 and 13 and placed in the transverse slot 15. The hanger is then swung inwardly into its limiting position, as shown by the dot and dash lines at 18 in Figure 4. While the hanger is in such position, a keeper for locking the hanger within the jaws is slid endwise into its locking position, as shown particularly in Figures 3 and 7. The keeper or key is provided with a tongue 90 portion 19 which occupies the space between the jaws 12 and 13 and which has a transversely arranged semi-cylindrical groove 25 which receives the upper half of the upper 95 horizontal hanger portion 16. It is apparent, therefore, that so long as the keeper is retained in place, it is impossible for the hanger to be dislodged from its normal supported position. It will be noted that the keeper 19 is provided with a tail 20 which is curved and conforms generally to the undercurved surface of the lower jaw 13. This tail 20, when the hanger is in any of its normal operating positions, lies between the downwardly extending arms 17 of the hanger. In other words, the keeper which locks the horizontal portion 16 of the hanger 100 in its support, in turn is locked in its re-

95

100

105

taining position by virtue of the fact that the keeper tail 20 is locked between the downwardly extending arms 17 of the hanger for preventing endwise displacement 5 of the keeper. As shown in dotted lines in Figures 3 and 7, the hanger portion is inwardly beyond the keeper tail 20 to permit application and withdrawal of the keeper. Said position corresponds to the position 10 shown at 18 in Figure 4. The dotted line position of the brake hanger, in Figure 4, is the position of a hanger when new shoes are in the brake heads and a three-eighth inch clearance is provided between the brake 15 shoes and the wheel. The position in full lines in Figure 4 is the position of the hanger when there is no shoe and the brake head is bearing against the wheel. The normal operating position, of course, is intermediate the two last positions mentioned. 20

By means of the arrangement hereinabove described the brake head may be quickly and easily applied to the support and withdrawn therefrom, the hanger 25 locked in position by the keeper, and the keeper in turn locked in position by the hanger so that in effect it is an interlocking arrangement.

When a new hanger is applied for replacing an old one, it is conceivable that an unskilled or careless worker might not replace the keeper in its locking position, in which event there is the possibility that the brake hanger might be thrown out of its bracket, 30 resulting in a falling of the brake mechanism and a possible wreckage of a train.

To prevent such an occurrence an addition has been made to the arrangement shown in Figures 1, 2 and 3 and which is 40 shown in Figures 5, 6 and 7. In said latter figures it will be noted that the upper jaw 12 is provided with an apertured ear 21 in which a rivet 22 is secured. The keeper is provided with an elongated ear 23 having 45 an elongated slot 24 therein in which an enlarged portion of the rivet 22 is loosely received. It is apparent, therefore, that while the keeper is free to slide endwise between operative and inoperative positions when the 50 hanger is in its innermost position for permitting such movement of the keeper, it is impossible accidentally to withdraw the keeper from the bracket. Accordingly when the bracket hanger is applied to its 55 supporting bracket, the keeper is always there for workmen to set in position.

It is my intention to cover all modifications of the invention falling within the spirit and scope of the following claims.

60 I claim:

1. In brake mechanism, the combination of a brake hanger support having an opening, a brake hanger having a portion which passes through said opening in a given plane 65 when the former is being applied to said

support, and a keeper in said opening for preventing displacement of said hanger by movement of said hanger in the same plane, said keeper in turn being retained in position by said hanger. 70

2. In brake mechanism, the combination of a brake hanger support having an open side and a groove, a brake hanger having a portion passing through said open side when the former is applied to said support and resting in said groove, and a keeper movably mounted in said open side for preventing displacement of said hanger, said keeper in turn being retained in position by said hanger. 75

3. In brake mechanism, the combination of a brake hanger support having spaced jaws, a hanger mounted between said jaws and applied therebetween by a movement in a given plane, and a keeper in said jaws for retaining the hanger in position against movement in the same plane, said hanger in turn cooperating to retain the keeper in locking position. 80

4. In brake mechanism, the combination of a brake hanger support having upper and lower jaws, the lower jaw having a groove therein for the reception of a brake hanger, a brake hanger mounted in said groove, and a keeper having a portion passing between said jaws and a groove fitting over a portion of the hanger within said jaws for retaining the hanger in position, said keeper and hanger having cooperating portions whereby the keeper normally is retained in its locking position. 90

5. In brake mechanism, the combination of a brake hanger support having upper and lower jaws, a brake hanger placed between said jaws by a movement in one direction, and a keeper retaining said hanger within said jaws passed into locking relationship with respect to said support and hanger in another direction. 105

6. In brake mechanism, the combination of a brake hanger support having upper and lower jaws, a brake hanger placed between said jaws by a movement in one direction, a keeper retaining said hanger within said jaws passed into locking relationship with respect to said support and hanger in another direction, and means whereby the keeper can be applied only when the hanger is in a given position. 110

7. In brake mechanism, the combination of a brake hanger support having spaced jaws, a brake hanger received between said jaws, and a keeper having an interlocked relationship with said support and hanger whereby the hanger is prevented from accidental displacement, said support and keeper being movably interconnected whereby the keeper may be moved from one position to another but never disconnected from each other. 115

8. In brake mechanism, the combination of a brake hanger support having spaced jaws, a hanger mounted therein, and a keeper associated with said jaws for retaining the hanger in position against accidental displacement, said support and keeper having a slot and pin connection whereby

the keeper may be moved from one position to another but may not be disconnected from said support.

Signed at Chicago, Illinois, this 7th day of April, 1923.

FREDERIC H. BENDER.
